(57) **CLAIM**

The ornamental design for a bucket stand base, as shown and described.

DESCRIPTION

FIG. 1 illustrates a top, front, left perspective view of a bucket stand base showing the new design;

FIG. 2 illustrates a bottom, rear, left perspective view thereof;

FIG. 3 illustrates a top, front perspective view with environment thereof;

FIG. 4 illustrates a front elevation view thereof, rear elevation view is a mirror image thereof;

FIG. 5 illustrates a left elevation view thereof, right elevation view is a mirror image thereof; and,

FIG. 6 illustrates a top plan view thereof; bottom plan view is a mirror image thereof.

The broken lines in FIG. 3 illustrate the surrounding environment. The hydroponic bucket, nesting edges, handles, structural components, and the inline pipe connections, shown in broken lines in FIG. 3, form no part of the claimed design.

1 Claim, 5 Drawing Sheets
